UNITED STATES PATENT OFFICE.

CHARLES E. DUFFIE, OF OMAHA, NEBRASKA.

ELECTRIC SIGNAL APPARATUS.

No. 920,932.

Specification of Letters Patent.

Patented May 11, 1909.

Application filed April 27, 1907. Serial No. 370,590.

To all whom it may concern:

Be it known that I, CHARLES E. DUFFIE, a citizen of the United States, residing at Omaha, in the county of Douglas and State 5 of Nebraska, have invented certain new and useful Improvements in Electric Signal Apparatus, of which the following is a specification.

This invention relates to means for notifying 10 the engineer or motorman of a railway train of danger conditions along the right-of-way, such as the presence of another train or car in too close proximity, misplaced switches, open draw-bridges, broken or missing rails, etc.

One of the objects of this invention is the provision of an improved signal apparatus which shall be entirely automatic in its action.

20 Another object of the invention is the production of a signal apparatus which shall give a danger signal if any portion of the apparatus is deranged.

The invention also relates to a signal system 25 comprising signal apparatus along the right-of-way and improved means carried by the locomotive for noting the condition of said apparatus for the purpose of obtaining a signal.

30 The invention also refers to the other improvements in signal systems and apparatus hereinafter set forth.

In the accompanying drawings, Figures 1, 2 and 3 are portions of a diagram illustrating 35 the circuits comprised in an embodiment of my invention. Figs. 4 and 5 are diagrammatic representations of contact brushes carried by the locomotive, and the circuits in which they are included.

40 In the signal system herein shown, signals are transmitted to the engineer at points along the right-of-way which I shall denominate signal stations A, B, C, D, E, etc., (stations A, B, and C only, being shown in the drawings) said signal stations being preferably located one-half mile apart. The traffic rails are divided into sections by means of insulating joints at the signal stations. Preferably midway between the signal stations 45 are placed the batteries and relays which control the electrical instruments at the signal stations. The points at which said batteries and relays are located I will term battery stations, and they are indicated in the drawings

5 by the letters a, b and c. I shall herein use the term "train" to indicate a steam or electric locomotive, car, or train of cars.

The track at each signal station is divided into two long and two short sections by means of insulating joints x. The short section to the left or west of the center of the signal station is composed of the rails 1 and 2. The adjoining and longer section immediately to the right or east consists of the rails 3 and 4. The longer section immediately east comprises the rails 5 and 6, and the second short section, the rails 7 and 8. On either side of the shorter insulated sections are two sections formed by the rails 9 and 10, and 11 and 12, said long sections extending 60 to the insulating joints placed immediately opposite each of the battery stations.

Upon each locomotive intended for service 65 upon a railway provided with a signaling system of this or any other suitable character is placed apparatus adapted to be electrically connected at each of the signal stations along the road with a comparatively short circuit which shall be herein termed the contact circuit. If said contact circuit is closed and 70 otherwise in operative condition, the apparatus carried by the locomotive will not be affected, and no danger signal will be given. If the contact circuit is open or deranged, the apparatus upon the locomotive will be operated 75 to give a danger signal. Said contact circuit is arranged to be opened and closed by apparatus included in a signal circuit extending, in this instance, from said signal station to the third signal station ahead. Said signal circuit, in turn, is arranged to be broken 80 and closed by relays included in a number of circuits of which the track rails and the car wheels and axles form a part. Said track circuits will next be described.

90 The rails 11 and 12 are connected at their left or west ends with a relay 13 by means of wires 14 and 15, the east ends of said rails being connected with a battery 16 by means of wires 17 and 18; the armature of a relay 19 being included in said wire 18. The relay 19 is connected with the rails 1 and 2 by means of the wires 20 and 21. Said rails 1 and 2 are connected with a battery 22 by means of wires 23 and 24. The rails 3 and 4 are connected at their west ends with an electromagnet 25 by wires 26 and 27. Upon the armature of magnet 25 is a locking projection

25^a adapted to engage the armature of the relay 19 and prevent said relay-armature from contacting its contact point.

The rail 4 is connected at its east end with 5 one terminal of a battery 28, the other terminal of said battery being connected by means of a wire 29 with a relay 30. A wire 31 connects the relay 30 with the east end of the rail 3. The rails 5 and 6 are similarly connected 10 with a battery 32 and relay 33 by means of wires 34 and 35, and with an electromagnet 36 by means of wires 37 and 38. The rails 7 and 8 are connected with a battery 39 by means of wires 40 and 41, and with a relay 42 by means of wires 43 and 44. The west ends of rails 9 and 10 are connected with battery 45 by means of wires 46 and 47, the wire 47 including the armature of the relay 42. The east ends of rails 9 and 10 20 are connected with a relay 48 by means of wires 49 and 50.

In the present embodiment, the resistance of the magnets 25 36 is higher than that of the relays 30 33, but the resistance of both, 25 when connected in series, preferably does not exceed four ohms. The current passing through the coils of the magnet 25 will then be sufficient to cause it to attract its armature, while the high resistance of said magnet 30 will cut down the flow of current to such an extent that the relay 30 will not attract its armature. However, the magnets 25 36 and the relays 30 33 may be of the same resistance, in which case said relays normally will 35 always attract their armatures, and this is perhaps the preferable arrangement, for a reason which will presently appear.

The signal circuits will now be described. At the signal station A a relay 51 is connected 40 with the common return wire 52 and with a signal wire 53 extending to the third signal station west of signal station A, a relay similar to relay 51 being there connected in series with said signal wire 53 and the common return wire 52. At the signal station A another relay 54 is connected in series with the common return wire 52 and a signal wire 55 running eastward to signal station D (not shown), a similar relay being there connected 45 in series with said signal wire and the common return wire. Similarly at signal station B a relay 56 is connected in series with the common return wire 52 and a signal wire 57 extending to the third signal station west 50 of signal station B. At signal station B another relay 58 is connected in series with the common return wire and a signal wire 59 running eastward to signal station E. At signal station C the relay 60 is connected with the 55 return wire 52 and a signal wire 61, extending to the third signal station to the west, and a relay 62 is connected with common return and a signal wire 63 extending eastward to signal station F. The contact points 64 of 65 the relays 51 54; 56 58, and 60 62 are connect-

ed with the common return wire 52 by means of the wires 65. The contact points 66 of the relays 30 and 33 are connected by means of a wire 67, between which wire and the common return wire 52 a relay 68 is connected in parallel. In this instance, at each side of said relay 68 a battery 69 is included in the wire 67. A single battery may, however, be made to serve the same purpose as the two batteries 69, the single battery being connected in series with the relay 68 in the short wire connecting said relay with the common return wire. The armatures 70 of the pairs of relays 51 and 33, 30 and 54, 56 and 33, 30 and 58, 60 and 33, and 30 and 62 are electrically connected. 70 75 80

In each of the signal wires 53, 55, 57, 59, 61 and 63 is placed a main battery 71 connected in parallel with the common return wire 52, said batteries being located at the 85 battery stations. At opposite sides of said battery relays 72 and 73 are included in said signal wire, the contact points of said relays being connected with said signal wire and the common return wire by means of wires 90 74 and 75. Each of the signal wires 53, 55, 57, 59, 61 and 63 is connected with the armatures of the relays 13 and 48, the springs of said relays tending to move said armatures in the direction to open said wires. 95

I will next describe the contact circuit at each of the signal stations. At each signal station there is placed along the track at a short distance outside of the traffic rails two contact rails 76 and 77 preferably of inverted 100 V - shape in cross - section. These contact rails are arranged to be contacted by suitable brushes carried by the locomotive, said brushes being electrically connected with cab apparatus to be described later herein. The 105 contact rail 76 is connected with the armature of the relay 68 by means of the wire 78. The contact rail 77 is connected with the contact point of said relay by means of the wire 79, said wire including a resistance 110 coil 80.

The means for electrically connecting the apparatus carried by the locomotive with the contact circuit consists, in this embodiment, of two pairs of contact brushes 81 and 82 115 attached to the oil boxes of the rear tank wheels, one pair being placed at each side of the tank. Said brushes are pivotally mounted at 83 and comprise curved cross-bars 84, one end of each of which cross-bars is engaged by an insulated spring 85 tending to maintain the brushes in a vertical position. The opposite ends of said cross-bars are arranged to contact flat contact springs 86. 87 are insulated adjusting screws for adjusting the position of said contact springs. 120 125

At a suitable point upon the locomotive is placed a battery 88, one pole of which is connected preferably with the lower ends of the contact brushes 81 by means of the wire 89. 130

The wire 89 is thus connected with the lower ends of the brushes so that the current shall traverse the entire length of the brush in order that in case the brush is accidentally 5 broken, the flow of current will be interrupted. When the brushes are not in contact with the contact rails 73 77, and therefore in the position shown in Fig. 4, the current from the battery 88 passes from the 10 lower end of each brush 81 to the cross bars of said brushes, thence into the contact springs 86, thence into the contact screws 90, thence through the wires 91 to one end of the resistance coil 92. The other end of said 15 resistance coil is connected by means of the wires 93 with the contact screws 94, the current flowing from said screws to the contact springs 86, the brushes 82, and the wire 95 to one end of the coil 96 of a differential relay 20 97. The other end of said coil is connected with the battery 88 through the wire 98. (Fig. 3). The other coil 99 of the differential relay 97 is connected with the battery 88 by means of the wires 100 and 98, a resistance 25 101 being connected in series with said coil and said battery. The armature 102 of said differential relay is connected with the battery 88 by means of the wires 103 and 100. The contact point 104 of said relay is connected with one end of the winding of an 30 electro-magnet 105, the other end of said winding being connected with the coils of the differential relay 97 and the battery 88 by means of the wires 106, 98 and 100. The spring 107 tends to close a circuit from the battery 88 through the electro-magnet 105. Said electromagnet is arranged to control 35 a suitable signaling device (not shown), such as means for setting the air brakes, the apparatus being so arranged that when the electro-magnet is deenergized the signal apparatus is rendered effective. The resistances 80, 40 92 and 101 are so adjusted that the resistances of the circuit through the battery 88 and the differential-relay coil 99, the circuit through said battery and the differential-relay coil 96 when the resistance 92 is included, and of said last-mentioned circuit 45 when the contact circuit is included, are substantially equal.

In the construction herein illustrated, the wires 91 constitute a connection between the brushes 81, and the wires 93 form a connection between the brushes 82. As shown, the 55 wires 91 and 93 are connected through the resistance 92. It will be seen that when the leading brush of each pair touches one of the contact rails and breaks the electrical connections at 86 90 and 86 94, a circuit will 60 still be complete through the coil 96 of the differential relay until the trailing brushes strike the contact rails. Thus, if one set of brushes should jump and leave the rails, the other set will keep the circuit closed and prevent a false danger signal being given.

In Figs. 1, 2 and 3 are shown successive portions of a signal system embodying my invention, the live circuits being indicated in heavy lines and the dead circuits in light lines. The track circuits are shown in normal condition in Fig. 2. Rails 11 and 12 are included in the circuit comprising the relay 13, battery 16, and the relay point of the relay 19. The relay 19 is in circuit with the rails 1 and 2 and the battery 22. The western ends of the rails 3 and 4 are connected with the electro-magnet 25, the armature of which carries the locking projection 25^a adapted to engage with the armature of the relay 19 for holding the relay points of said relay open.

It will be seen that so long as the rails 11 and 12 are electrically continuous and unoccupied by a pair of wheels the relay 13 will be energized by the current from battery 16, 85 and will attract its three armatures, closing the points of said relay as shown in Fig. 2, and making the signal wires 55, 57, and 61 electrically continuous. But the relay 13 will not be energized unless the relay points 90 of the relay 19 are closed so as to complete the circuit of the battery 16. Said points will be closed so long as the circuit is completed from the battery 22 through the rails 1 and 2 unless while the armature of the relay 19 is in its uppermost position, the magnet 25 is deprived of current, in which case the locking projection 25^a upon the armature of said magnet will engage the armature 95 of the relay 19, and hold it open. The purpose of this interlock will be explained hereinafter.

Normally, current from the battery 28 will flow through the rails 3 and 4 and the wires 26 and 27 to the magnet 25 and through 105 the wires 29 and 31 to the relay 30. The magnet 25 being of much higher resistance than the relay 30, the flow of current through the coils of said relay 30 is reduced to such an extent that said relay normally does not attract its armature. Assuming now that a pair of wheels contact the rails 11 and 12, the electrical conditions just described will be altered to those illustrated in Fig. 1.

The wheels y have short-circuited battery 16 and thus deprived relay 13 of current, breaking the signal wires 53, 57 and 61. Said signal wires also would be opened by the presence of a pair of wheels across the rails 1 and 2, said wheels short-circuiting the battery 22, thus depriving the relay 19 of current, and breaking the circuit in which the relay 13 is included. If now, while there is a pair of wheels across the rails 1 and 2, a second pair of wheels enters upon the rails 3 and 4 (as would occur in the case of a train traveling in the direction of the arrow, Fig. 1), a short circuit will be established through the pair of wheels upon the rails 3 and 4 and through the wire 31, relay 30, wire 29, and 125 wire 33, thus closing the circuit of the magnet 25 and holding the relay 30 in its uppermost position, 130

battery 28, depriving the magnet 25 of current, whereupon its armature will be released and the locking projection 25^a will engage the armature of the relay 19 which has 5 previously receded. The circuit through battery 16 and the relay 13 cannot now be again closed, even though the short circuit across the rails 11 and 12 be removed, so long as the magnet 25 is deprived of current. 10 The same short circuit, however, that deprived said magnet 25 of current cuts out the resistance of said magnet, increasing the amount of current flowing from battery 28 through the relay 30, which relay then attracts its armature, as indicated in Fig. 3. 15 As soon as the short circuit is removed from across the rails 3 and 4, the magnet 25 again receives current, and, attracting its armature, permits the armature of the relay 19 to close the circuit through the relay 13 and close the signal wires 53, 57 and 61 through the armature and relay points of said relay. Precisely similar electrical conditions obtain 20 to the right of any signal station upon the approach of a train, but affecting, however, 25 the relays 33, 48 and 42 and the magnet 36.

Having now described the operation of the instruments in the track circuits, the operation of the signal circuits will next be explained. 30 Referring to battery station *b* (Fig. 2): The battery 71 at this point is connected in the signal wire 61 extending to signal station C and is connected in parallel between said signal wire and the common 35 return wire 52. A part of the current from said battery flows through the relay 72 to the relay points of the relay 48 at battery station *b* and the relay points of the relays 13 and 48 at battery station *a* to the relay 40 corresponding to relay 54 at the signal station (not shown) next west of signal station A, thence to the common return wire and back to battery 71 at battery station *b*. The remainder of the current from said battery 45 flows east through the relay 73, the relay points of the relay 13 at battery station *b*, the relay points of relays 48 and 13 at battery station *c* through the relay 60 at signal station C, thence to common return wire 52 50 and back to battery 71 at battery station *b*. It will be seen that so long as current is flowing in each direction from said battery 71, the relay before referred to at the signal station next west of signal station A and the 55 relay 60 at signal station C will both be energized and will attract their armatures 70, making an electrical connection between said armatures and the wires 65. If, however, the signal wire 61 be open at any point 60 between battery station *b* and the signal station next west of signal station A, the relay before referred to at said signal station and the relay 72 at battery station *b* will both be deprived of current. When the armature of 65 the former relay drops the circuit between

said armature and its wire 65 will be opened. The dropping of the armature of the relay 72 at battery station *b* will have the following effect. A circuit will be closed from the battery 71 through wires 52 and 74, the armature of the relay 72, wires 75 and 61, and relay 73. This will short-circuit the current from battery station *b*, and it can no longer flow to the relay 60 at signal station C. The latter relay, thus deprived of current, will allow its armature to fall, and the circuit will be broken between said armature and the wire 65 leading to the common return wire 52. A break in the signal wire 61 at a point east of the battery station *b* will, of course, 70 have the same effect on the relays at signal station C and the signal station next west of the signal station A, except that in this event the short-circuit would be formed by the relay 73 and would occur between the battery station *b* and said last-mentioned signal station. It will be observed however, that when the current from the battery 71 at battery station *b* is short circuited as first described, said current continues to flow 75 through the coils of the relay 73 at said battery station because said short circuit is formed outside of the connections of said relay. As soon, however, as the circuit is restored between the battery 71 at battery 80 station *b* and the signal station next west of signal station A, the relay 72 will again be energized, and, attracting its armature, will remove the short circuit between the battery 71 at battery station *b* and the signal station 85 C, and current will again be permitted to flow east to the relay 60 at said signal station 90 C.

It will now be seen that a pair of wheels 95 across the rails at any point between signal station C and the signal station next west of signal station A, will deprive both the relay 60 and the relay corresponding to 62 at said last mentioned signal station, of current, the first by an open circuit and the other by a 100 short circuit, or the reverse, according to where the train stands on the track between said signal stations. The breaking of a 105 track circuit at any point between the said two signal stations will have the same effect, and this will happen not in one only, but in the three signal circuits, because each relay 110 13 48 governs three separate signal circuits.

As hereinbefore explained, in this embodiment of the invention, the relays 30 33 at the 115 signal stations do not receive enough current to enable them to close a circuit from one of the batteries 69 through the relay 68 until a train enters upon the rails 3 4 or 5 6, and it 120 will be remembered that the approach of the train will have made impossible the closing of a circuit from one of said batteries through the relay 68 because of the deenergizing of the relay 51 54, 56 58, 60 62, depending upon the direction in which the train approached. 125 130

If, now, the other one of the relays 51 54, 56 58, 60 62 has been deenergized by the opening of the signal circuit extending to the third signal station ahead, it will be apparent 5 that the relay 68 at the signal station being approached cannot be energized, and therefore that the contact circuit at said signal station will be open.

Referring now to Figs. 3, 4 and 5, the operation of the contact circuits and the circuits upon the locomotive will be explained. When the brushes 81 and 82 are not in contact with the contact rails 76 77 at a signal station, a circuit is complete through the brushes 81, 10 the wire 89, the battery 88, wire 98, coil 96 of the differential relay 97, wire 95, brushes 82, contact springs 86, contact screws 94, wires 93, resistance 92, wires 91, contact screws 90, and contact springs 86 back to brushes 15 81. Another circuit is complete through the battery 88, wire 100, coil 99 of the differential relay 97, resistance 101 and wire 98 to the battery 88. As hereinbefore mentioned, the resistances 92 and 101 are adjusted so that 20 the resistances of the two circuits just described shall be the same. An equal amount of current, therefore, passes through both of said differential-relay coils, and no magnetism is developed in the core of the relay 97, 25 which, consequently, does not attract its armature 102. A third circuit is complete from the battery 88, through wires 100 and 103, armature 102, contact 104, electro-magnet 105, and wires 106 and 98, back to said 30 battery. The electro-magnet 105, therefore, is energized, and, attracting its armature, holds the signal device in the inoperative position.

When the locomotive passes a pair of contact rails 76 77, the brushes 81 82 will be swung upon their pivots 83 by the contact of their lower ends with said rails, withdrawing one of the contact springs 86 for each pair of brushes from the contact screws 90 and 94, 40 thus breaking the short circuit between said contact brushes through the resistance coil 92 and replacing said short circuit with the contact circuit leading from the contact rail 76 through wire 78, resistance 80, and wire 45 79, to the contact rail 77; assuming the last mentioned circuit to be closed by the relay 68. Since the resistances of the two circuits referred to are equal, the amount of current flowing through the two coils of the differential 50 relay 97 will not be altered, and the cab 55 circuits will remain in the condition first described and as shown in Fig. 1. If, however, the contact circuit has not been closed by the relay 68 at the signal station in question, the 55 coil 96 of the differential relay will be deprived of current, the armature 102 of said differential relay attracted, and the circuit through the electro-magnet 105 broken, operating the signal device.

60 The resistance 80 is included in the contact

circuit so that an accidentally or maliciously formed short circuit cutting out said resistance shall be detected by the unbalancing of the currents in the windings of the differential relay 97. To render such detection certain 70 the resistance 80 should be inserted as near as possible to the relay points of the relay 68.

The magnets 25 and 36 are employed to prevent a misleading clear signal being given 75 to a locomotive drawing no load. The rear wheels of such an engine would have left the rails 7 and 8 (or 1 and 2) before the contact brushes 81 82 touch the contact rails 76 77. This would allow the track circuits of rails 7 80 9 10 (or 1 2 11 12) to close, closing the signal circuit extending rearwardly of the engine, energizing relay 51, 54, 56, 58, 60 or 62 in said circuit, closing a circuit through battery 69 and relay 68, and closing the contact 85 circuit. A clear signal would then be given, said signal coming from the portion of the train-control block behind the engine, even if there were a train in the portion of said block ahead of the engine. It is therefore 90 necessary, for the protection of light engines, to keep the relay 54 58 62 (or 51 56 60) deprived of current under all conditions until the contact brushes have passed off the contact rails.

To prevent the giving of a false danger signal by the train itself at every signal station, the rails 3 4 5 6, in the present embodiment of the invention, should be longer than the distance from the front truck of the longest 100 engine which passes over the road to the rear wheel of the tender, the preferred length being not less than 90 feet.

In order that there may be no points at which two trains could meet without getting 105 signals, I arrange the signal circuits so that they overlap each other, as shown, one of the two signal circuits that end at each signal station extending to the third signal station ahead, and the other circuit running to the 110 third station behind. The reason for two overlaps instead of but one is to provide against the remote possibility of two approaching trains striking and leaving the contact rails at stations A and D, for example, before the one train reached the rails 7 8 (station A) or the other, the rails 1 2 (station D). Neither train having reached 115 said track rails before the other left the contact rails, neither would operate the track-circuit apparatus to open the signal wire 55 in time to signal the other. The trains would then proceed to stations B and C where they would be stopped, as the signal relays governing these two stations would be deener- 120 gized before either train arrived.

It will be seen that a train receives signals only from the signal circuits extending forwardly from any particular signal station, but that it transmits signals to stations 130

ahead of and behind it. Any train therefore as it moves over the track is practically the center of a movable train-control or signal block three miles long, which shifts forward, 5 as the train progresses, every half mile.

In the construction herein shown, the resistance of the magnets 25 36 is higher than that of the relays 30 33, said relays not receiving sufficient current to cause them to 10 attract their armatures until said magnets have been deprived of current by a train, as hereinbefore described. The relay 68, therefore, normally is not energized and the contact circuit is open. As relays are sometimes sluggish in operation, the arrangement just described necessitates making the rails 15 3, 4, 5, and 6 longer than would be required if the relay 68 was normally energized. It being desirable to make the track circuits as 20 short as practicable in order to reduce the amount of escape or loss of current, the resistance of the magnets 25 36 and relays 30 33 may be made substantially equal, in which case said relays normally will attract their 25 armatures, and the contact circuits remain closed except in case of danger.

For convenience, I have herein used the term "battery" to indicate any suitable source of electrical energy, and the term 30 "relay" to designate various equivalent forms of apparatus.

It will be apparent to those skilled in the art that the circuits and apparatus herein shown may be altered and rearranged in 35 various ways without departing from the spirit and scope of my invention. No undue limitation, therefore, should be understood from the foregoing detailed description.

40 The track circuits herein disclosed are claimed in my copending application Serial No. 389,187, filed August 19, 1907.

I claim as my invention:

1. In a railway signal apparatus, in combination, a normally inactive differential relay, the circuits through which are normally closed; a signal device controlled by said relay; said relay and said signal device being arranged to travel along the right-of-way; 45 and means for affecting one of said relay circuits to unbalance the currents in said circuits.

2. In a railway signal apparatus, in combination, a closed circuit comprising one coil 55 of a differential relay; a normally closed circuit comprising the other coil of said relay, said circuits being of substantially the same resistance; a signal controlled by said relay; said relay and said signal being arranged to 60 travel along the right-of-way; and means for opening said second mentioned circuit.

3. In a railway signal apparatus, in combination, a permanently closed circuit comprising one coil of a differential relay; a cir-

cuit comprising the other coil of said relay, 65 said circuits being of substantially the same resistance; means for affecting the flow of current in one of said circuits; and a signal device controlled by said relay; said relay and said signal device being arranged to 70 travel along the right-of-way.

4. In a signal apparatus, in combination, a complete circuit comprising one coil of a differential relay; a complete circuit comprising 75 the other coil of said relay; a signal device controlled by said relay; a signal circuit; apparatus controlled by said signal circuit; and means for including said last mentioned apparatus in one of said differential-relay circuits.

5. In a signal apparatus, in combination, a circuit comprising one coil of a differential relay; a circuit comprising the other coil of 85 said relay; a signal device controlled by said relay; a signal circuit; a contact circuit controlled by said signal circuit; and means for including said contact circuit in one of said differential relay circuits.

6. In an electric signal system, in combination, a signal device; an electromagnet 90 controlling said device; a differential relay controlling said electromagnet; circuits for said relay; an extension of one of said relay circuits; and means for including said extension in said circuit.

7. In an electric signal system, in combination a signal device; an electromagnet controlling said device; a differential relay controlling said electromagnet; circuits for said relay; a signal circuit; a contact circuit controlled by said signal circuit; and means for breaking one of the relay circuits and including in it said contact circuit.

8. In a signal apparatus, in combination; a circuit comprising a battery and one coil of a 105 differential relay; two contact devices and a resistance between said contact devices in series with said battery and the other coil of said differential relay; a signal device controlled by said relay; and means for breaking the circuit including said contact devices.

9. In a signal apparatus, in combination, a circuit comprising a battery and one coil of a differential relay; two contact devices and a resistance between said contact devices in 110 series with said battery and the other coil of said differential relay; a signal device controlled by said relay; and means for breaking the electrical connection between one of said contact devices and said resistance.

10. The combination, with two pivoted contact brushes of a resistance in series circuit in said brushes, said brushes being arranged, when pivotally moved, to break the circuit at a point between them for cutting 115 out said resistance.

11. In a signal apparatus, in combination, a signal device; a differential relay control-

- ling said device; a normally closed circuit of variable length through said relay; and means for varying the length of said circuit. 65
12. In an electric signal system, in combination, a signal device arranged to travel; a differential relay controlling said device; a normally closed circuit for said relay; an extension of said circuit; and a contact device traveling with said signal device for includ- 10 ing said extension in circuit. 70
13. In a signal apparatus, in combination, a signal device; a differential relay controlling said device; contact devices in circuit with said relay; a short circuit between said 15 contact devices; and means operated by said contact devices for breaking said short circuit. 75
14. In a railway signal system divided into a plurality of blocks, in combination, a signal 20 circuit extending from one block to another; and signal apparatus arranged to move along the right-of-way, and comprising a differential relay with its circuits, and a signal device controlled by said relay, said signal circuit being arranged to affect one of the differential-relay circuits to unbalance the currents in said differential-relay circuits. 80
15. In a railway signal system divided into a plurality of blocks, in combination, a signal 25 circuit extending from one block to another; signal apparatus arranged to move along the right-of-way, said signal apparatus comprising a differential relay with its circuits, and a signal device controlled by said relay; and contact means arranged to be operatively connected with said differential relay, said contact means being controlled by 30 said signal circuit. 85
16. A railway signal apparatus arranged 35 to move along the right-of-way and comprising a differential relay with its circuits, and a signal device controlled by said relay; and stationary means located on the right-of-way for operating said differential relay. 90
17. A railway signal apparatus arranged 40 to move along the right-of-way and comprising a differential relay with its circuits, and a signal device controlled by said relay; and stationary means located on the right-of-way for opening one of the differential-relay circuits. 95
18. A railway signal apparatus arranged 45 to move along the right-of-way and comprising a differential relay with its circuits, and a signal device controlled by said relay; means located on the right-of-way for opening one 50 of the differential-relay circuits; and a circuit located on the right-of-way and adapted to be included in the last mentioned differen- 55 tial-relay circuit. 100
19. A railway signal apparatus arranged 60 to travel along the right-of-way and comprising a differential relay with its circuits, and a signal device controlled by said relay, one of 65 the differential-relay circuits being permanently closed; and stationary means on the right-of-way for opening the other differential-relay circuit. 70
20. A railway signal apparatus arranged 75 to move along the right-of-way and comprising a differential relay with its circuits, and a signal device controlled by said relay, one of said differential-relay circuits being permanently closed; mechanical means located on the right-of-way for opening the other differential-relay circuit; and a contact circuit on the right-of-way adapted to be included in the last mentioned differential-relay circuit. 75
21. A railway signal apparatus arranged 80 to move along the right-of-way and comprising a differential relay with its circuits, and a signal device controlled by said relay, one of said differential-relay circuits being permanently closed; means located on the right-of-way for opening the other differential-relay circuit; a contact circuit on the right-of-way adapted to be included in the last mentioned differential-relay circuit; and a signal circuit controlling said contact circuit. 85
22. A railway signal apparatus arranged 90 to move along the right-of-way, comprising a signal device; an electromagnet controlling said signal device; a differential relay, with its circuits, controlling said electromagnet; and a contact brush included in one of the differential-relay circuits. 95
23. The combination with two contact rails, of two movably supported brushes, each adapted to contact one of said contact 100 rails; a circuit in which both of said brushes are included; and means operated in the movement of said brushes for breaking said circuit at a point between said brushes. 105
24. In a signal apparatus, in combination, cab circuits comprising a differential relay and a source of electrical energy; a cab circuit comprising a magnet; a signal device controlled by said magnet, said relay being arranged, when energized, to break said last 110 mentioned circuit, all of the foregoing apparatus being arranged to travel; stationary means arranged to be electrically connected with said traveling apparatus; and stationary means, electrically independent of the other 115 stationary means, for controlling the latter. 115
25. The combination, with a circuit, of a pivotally mounted contact device permanently connected with the circuit near its free end. 120
26. The combination, with a circuit, of a pivotally mounted contact device permanently connected with the circuit near its free end, said device having a breakable connection with the circuit at another point. 125
27. The combination, with two movably supported contact brushes, of an electrical connection between said brushes arranged

to be broken by the movement of said brushes.

28. The combination, with two movably supported contact brushes, of an electrical connection between said brushes arranged to be broken by the movement of said brushes, and an electric circuit in which said electrical connection and the free ends of said brushes are included.

10 29. The combination, in a locomotive signal apparatus, of a leading and a trailing contact brush at each side of the locomotive, said brushes being pivotally supported; an

electrical connection between the two brushes at each side of the locomotive, arranged to be broken by the pivotal movement of said brushes, said electrical connections being electrically connected; and a circuit containing signal means and joining the pair of brushes at one side of the locomotive 15 with the other pair. 20
